(57) **CLAIM**

The ornamental design for an eye massage device, as shown and described.

DESCRIPTION

FIG. 1 is a front side perspective view of an eye massage device showing my new design;

FIG. 2 is a rear side perspective view thereof;

FIG. 3 is a front side elevation view thereof;

FIG. 4 is a rear side elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is an enlarged partial view of "9" showing a hollow area of the eye massage device in FIG. 3.

The broken lines in the drawings depict portions of the eye massage device that form no part of the claimed design.

1 Claim, 9 Drawing Sheets
